UNITED STATES PATENT OFFICE.

JOHN CAMPBELL HODGE, OF CHICAGO, ILLINOIS, ASSIGNOR TO WESTERN ELECTRIC COMPANY, INCORPORATED, OF NEW YORK, N. Y., A CORPORATION OF NEW YORK.

TENSION DEVICE.

Application filed April 30, 1927. Serial No. 187,965.

This invention relates to tensioning devices, and more particularly to a device wherein a strand being unwound from a supply is tensioned by a frictional retarding force applied to the periphery of the strand supply.

The object of this invention is to provide a simple, efficient and readily adjustable device for maintaining material under a substantially constant tension as it is withdrawn from a supply.

In accordance with one embodiment of this invention as applied to a stranding apparatus for producing cables there is provided a pair of spaced spring actuated arms pivoted upon a common shaft and bearing at their free outer ends upon the periphery of a strand supply wound upon a revolvably mounted spool for exerting a predetermined frictional retarding force to the rotation of the spool as the strand is withdrawn therefrom so that a substantially constant tension is maintained on the strand throughout its entire length. The springs are of the torsion type and are completely enclosed within opposed housings formed integral with the hubs of the arms and concentrically disposed around the common shaft, one end of each of the springs being fixed to the hub of the associated arm, with the opposite end of the spring fixed to a flanged adjusting nut extending within and adjustably secured to an intermediate collar fixed to the shaft.

Other objects and advantages of this invention will become clearly apparent from the following detailed description, reference being had to the accompanying drawing, wherein

Fig. 1 is a fragmentary elevational view of a rotatable drum of a stranding apparatus with a strand supply spool revolvably mounted thereon and a strand tension device individual thereto and embodying the features of this invention associated therewith;

Fig. 2 is a side view thereof;

Fig. 3 is an enlarged section on the line 3—3 of Fig. 2, looking in the direction of the arrows;

Fig. 4 is a section on the line 4—4 of Fig. 3 looking in the direction of the arrows, and

Fig. 5 is a view similar to Fig. 1 on a reduced scale, showing another application of the invention.

In the drawing this invention is shown as

applied to a wire twisting or stranding apparatus such as is used in the manufacture of telephone cables. For a complete illustration and description of one type of stranding apparatus to which the present invention is applicable, reference may be had to Patent 1,579,769 to H. F. Jones, dated April 6, 1926.

Referring now to the drawing in detail, one unit or drum 10 of a stranding apparatus which is rotatable upon a horizontal axis is shown fragmentarily. The drum comprises a pair of spaced rings 11 each fixed to and adjacent the outer ends of a plurality of equally spaced angle irons 12 radiating from rotatable axial bearing members (not shown), to which the inner ends of the angle irons are secured. The rings 11 and angle irons 12 secured thereto are integrally united by a plurality of equally spaced horizontally disposed angle irons 13 fixed to the outer ends of the angle irons 12. Outside of each ring 11 is an endless member 14 providing a plurality of equally spaced bearings 15, one of which is indicated in Fig. 2 for supporting opposite ends of a spindle 16 upon which is rotatably mounted a strand supply spool 17. The endless members 14 are each formed from a plurality of similar members 18 secured to the outer ends of the angle irons 13. A suitable latch device 19 is provided at each of the bearings 15 for maintaining the spindle 16 stationary relative to the bearing, the spool 17 rotating on the spindle as the strand is withdrawn therefrom in the operation of the stranding apparatus, in a well known manner. It is to be understood that the various elements hereinbefore described and comprising the drum 10 are suitably secured together by electric welding or otherwise to form an integral structure.

A strand tension device 20 embodying the features of this invention, and which for illustrative purposes has been applied to a stranding apparatus will now be described.

Secured to the angle irons 13 between the inner opposed faces of the endless members 14 by a pair of spaced brackets 23 is a spindle 24, the spindle being held stationary with respect to the brackets by pins 25 (Fig. 3). Fixed to the spindle 24 intermediate the brackets 23 by a pin 26 is a sleeve-like member or collar 27. Fitting into annular channels 28 formed in each end face of the

collar 27 are shouldered adjusting nuts 29, the nuts being rotatably mounted on the spindle 24. The peripheral surface of each of the nuts 29 intermediate their end faces 5 is hexagonal in contour as indicated at 30 (Figs. 1 and 4), for a purpose which will be apparent as this description progresses. The inner shouldered portion of each of the nuts 29 fitting in the annular channels 28 10 of the collar 27 are provided with a plurality of equally spaced apertures 33 (Figs. 3 and 4) radially arranged in the peripheral surface thereof. Each of the apertures 33 in each nut 29 is arranged to be axially aligned 15 with one or another of a plurality of threaded apertures 34 formed in the peripheral surface of the collar 27 at either end thereof. After adjusting the tension device 20, which will be described shortly, a shouldered screw 35 is threaded into one of the apertures 34 at either end of the collar 27, shouldered ends 36 of the screws entering the apertures 33 of the nuts and thus locking 20 them to the collar. Pivotaly mounted 25 on the spindle 24 at either end thereof (Fig. 3) is an arm 37 provided at its pivotal portion with an integral tubular extension or housing 40, the opposite end surfaces of the housing abutting the opposed end surfaces 30 of the bracket 23 and the nut 29. The inner peripheral surface of the housing 40 at its inner end, which is open, is arranged to turn on an outer shouldered portion of the associated nut 29, while the opposite end of 35 the housing, which is closed, is journaled on the spindle 24. Encircling the spindle 24 between the outer end faces of the nuts 29 and the inner faces of the housings 40 at their closed outer ends and within which 40 they are completely enclosed are torsional springs 41, opposite ends of the springs extending into apertures 42 and 43 provided in the opposed faces of the housing 40 and the nut 29, respectively. The free ends of 45 the arms 37 are curved outwardly and form brake portions arranged to bear against the outer periphery of the strand wound on the spool 17 (Fig. 2) to exert a frictional retarding force or drag thereon during the 50 withdrawal of the strand therefrom, the strand being withdrawn in the direction indicated by the arrows (Fig. 2) in the particular application of the invention illustrated, the torsional springs 41 act to resiliently press the free ends of the arms against the strand. The frictional retarding force to be applied to the strand as it is withdrawn from the spool is determined by the strength and size of the strand. To adjust the pressure 55 of the arms 37 against the strand, the energy of the springs 41 may be varied in the following manner.

Referring to Figs. 3 and 4 the adjustment of the left hand arm 37 (Fig. 3) will be described. To increase the energy of the

spring 41 a suitable wrench is applied to the hexagonal portion 30 of the nut 29 and the locking screw 35 is then removed. Thereafter by rotating the nut 29 in a clockwise direction as viewed in Fig. 3 the energy or tension of the spring will be increased, a movement of the nut in a counter-clockwise direction permitting the spring to unwind. Upon increasing the tension of the spring 41 the desired amount, the screw 35 is threaded into one of the apertures 34 of the collar 27 with the shouldered end 36 thereof being inserted in the nearest aperture 33 in the nut 29, thereby locking the nut and collar together. It will be apparent from the inspection of Fig. 4 that a very fine adjustment of the tension of the spring 41 may be had, since the spacing between the centers of the apertures 33 and 34 is arranged in such a manner that comparatively little movement of the nut 29 from its set position in either direction, to increase or decrease the tension of the spring 41, there results a new alignment of the apertures 33 and 34.

The dotted line position of the arm 37 (Fig. 2) indicates the position thereof when the spool 17 is empty. In this position the free end of the arm 37 lies very close to the drum of the spool 17, the arm being retained in this position under the action of the spring 41 during the removal of the empty spool by a stop lug 44 formed on the arm engaging the edge face of the upper arm of the angle iron 13. It will be apparent that as the diameter of the strand wound on the spool decreases, the torsional spring 41 connected thereto acts to gradually decrease the pressure of the arm 37 upon the periphery of the strand, the pressure being reduced to a minimum when the arm is in the dotted line position. During the mounting of the filled spool 17 the arms 37 are automatically turned counter-clockwise due to the engagement of the periphery of the strand thereon with the curved outer ends of the arms as the spool is placed in position, the energy of the springs 41 thus being restored to provide the desired pressure of the arms against the periphery of the filled spool.

By using two independently tensioned arms 37 on each spindle 24 it is possible to mount a pair of spools, each containing strands of different strength, thus providing a brake arm 37 for each spool, a pair of spools mounted in this manner being illustrated in Fig. 5.

It should be understood that although the strand tensioning device of this invention is disclosed as applied to a strand supply of a stranding apparatus, the features thereof are applicable to various other strand supplies for different uses and the invention should be limited only by the scope of the appended claims.

What is claimed is:

justable member for holding the latter member in adjusted position, the two members provided with a plurality of radially arranged registrable apertures, and an element for insertion in the registered apertures.

8. In a device for maintaining a substantially constant tension in a strand being withdrawn from a supply thereof, a pair of 10 brakes for engaging the periphery of the supply, resilient means connected thereto for pressing the brakes against the supply, adjacent individual adjustable members

operatively associated with the resilient means for controlling the tensions thereof, 15 a stationary member intermediate the adjustable members and cooperating therewith for holding the latter members in adjusted positions, the several members provided with a plurality of radially arranged registrable 20 apertures, and a pair of elements for insertion in the registered sets of apertures.

In witness whereof, I hereunto subscribe my name this 23rd day of April A. D., 1927.

JOHN CAMPBELL HODGE.
